SHOE POLISH BOX

Filed May 5, 1921

FIG. 1.

FIG. 2.

FIG. 4.

Inventor

Thomas Lucien Taliaferro

By Sturtevant & Muson

Attorneys

UNITED STATES PATENT OFFICE.

THOMAS LUCIEN TALIAFERRO, OF CHICAGO, ILLINOIS.

SHOE-POLISH BOX.

Application filed May 5, 1921. Serial No. 466,998.

To all whom it may concern:

Be it known that I, THOMAS L. TALIAFERRO, a citizen of the United States, residing at Chicago, in the county of Cook, State 5 of Illinois, have invented certain new and useful Improvements in Shoe-Polish Boxes, of which the following is a description, reference being had to the accompanying drawing, and to the figures of reference marked 10 thereon.

The invention relates to new and useful improvements in a shoe polish box, and more particularly to a shoe polish box which may be readily opened by means of a 15 coin or other suitable instrument.

An object of the invention is to provide a box which is very simple in construction and which can be cheaply made, and wherein the projecting ribs which are used for 20 separating the cover from the body portion of the box are held spaced a definite distance apart by the shaping and forming of the lower edge portion of the cover.

In the drawings:—

25 Figure 1 is a side view of a shoe polish box having my improvements embodied therein;

Fig. 2 is a vertical sectional view through the box;

30 Fig. 3 is an enlarged vertical sectional view through a portion of the box, and

Fig. 4 is an enlarged top plan view of a portion of the box.

In carrying out the invention, I have provided a shoe polish box which is made in two pieces, a body portion formed of one integral piece of metal and a cover formed of a second integral piece of metal. The body portion at a short distance below its upper edge is bent so as to provide a horizontal outwardly extending rib. The cover engages the portion of the box above said rib and said cover is rolled at its lower edge outwardly and upwardly to form a projecting bead or rib, and the lower edge of said cover at spaced intervals is rolled to a less extent whereby downwardly projecting lugs are formed which engage the rib on the body portion of the box when the cover is placed 45 on the box, and holds the ribs on the cover and body portion of the box spaced so as to permit the insertion of a coin or other instrument for prying off the cover.

50 Referring more in detail to the drawings, my improved box consists of a body portion 1 and a cover 2. Said body portion 1 is

formed as above noted, of a single piece of metal which is bent to form a horizontally outwardly extending rib 3. Said rib is flattened at the upper face thereof as indicated 50 at 4 so as to provide a substantially horizontal flat surface, or a flat surface which is parallel with the plane of the outer edge of the body portion of the box. The cover is shaped so that its depending wall fits the 55 outer wall of the body portion above the rib 3 and frictionally grips the same so as to hold the cover on the box. The extreme lower edge of the cover is rolled outwardly and upwardly so as to form a bead or rib 70 5. The under face of this bead or rib 5 is flattened as indicated at 6. This enables the ribs 3 and 5 to be relatively close together and at the same time permit the insertion of a coin of sufficient diameter and thickness so that by turning the coin in the well-known way, the ribs may be pried apart, and thus the cover pried off from the 75 body portion of the box. In order to insure that the ribs 3 and 5 will be spaced a 80 sufficient distance to permit the insertion of the coin for the purpose stated, the lower edge of said cover at spaced intervals is rolled upwardly to a less extent thus forming relatively narrow spacing lugs 7, 7, preferably four in number, on a shoe polish box, 85 which lugs are adapted to engage the upper face of the rib 3 and thus positively holds the rib 5 spaced from the rib 3. In other words, the cover cannot be forced on to the 90 body portion of the box but what there is ample space between the ribs 3 and 5 to permit the insertion of the coin or other tool for the prying off of the cover. It is to be noted that these lugs 7, 7 are comparatively 95 short in length and this leaves a relatively wide space between adjacent lugs so that the instrument for prying off the cover may be applied at several points between the lugs, and the cover thus more quickly lifted. 100

It is obvious that minor changes in the details of construction may be made without departing from the spirit of the invention as set forth in the appended claim.

Having thus described the present invention, what I claim as new and desire to secure by Letters Patent, is—

A shoe polish box, comprising a body portion having an outwardly projecting rib in the side wall thereof, the said rib being disposed at a distance below the upper edge of said side wall, and a cover for frictionally 110

engaging the body portion of the box above said rib, said cover having its lower edge rolled outwardly and upwardly to form a projecting strengthening rib, said edge at 5 spaced intervals being rolled to a less extent, whereby relatively narrow downwardly projecting spacing lugs are formed adapted to engage the projecting rib on the body portion of the box and hold the rolled lower 10 edge of the cover a spaced distance from said projecting rib on the body portion of

the box, whereby the main frictional grip of the cover on the body portion is a slight distance away from the projecting rib on said body portion where the metal is more 15 flexible and thereby the cover may be more readily removed from the body of the box by a tool inserted between the projecting ribs for prying off the cover.

In testimony whereof, I affix my signature. 20

THOMAS LUCIEN TALIAFERRO.
